UNITED STATES PATENT OFFICE.

THOMAS A. GORMAN, OF JOHNSTOWN, PENNSYLVANIA.

FORGING MACHINE.

Application filed November 7, 1924. Serial No. 748,363.

To all whom it may concern:

Be it known that I, THOMAS A. GORMAN, a citizen of the United States, and resident of Johnstown, in the county of Cambria and State of Pennsylvania, have invented certain new and useful Improvements in Forging Machines, of which the following is a specification.

This invention relates to forging machines and more particularly to continuous motion or automatic forging machines for making balls and other similar articles from round bar stock.

Heretofore balls such as made by the improved machine of this invention have been made by power hammers or by an automatic machine costing thousands of dollars more than the present machine, and even with this expensive automatic machine the maximum output was considerably less than the output of the machine of this invention.

This invention has for its object the modification of a standard "Ajax" heavy duty heading machine, such as is well known and commonly used in the art for heading heavy bolts and the like, so as to form balls for use in crushing and grinding cement and other such material.

In the drawings—
30 Figure 1 is a top plan of a forging machine embodying my invention.

Figure 2 is a side elevation thereof.

Figure 3 is an enlarged fragmentary plan showing the ball forming mechanism.

35 Figure 4 is a sectional elevation on the line IV—IV of Figure 3.

Figure 5 is a sectional elevation on the line V—V of Figure 3.

40 Figure 6 is a fragmentary sectional elevation showing the shear blade, receiving block and stock gage.

Figures 7, 8 and 9 are sectional elevations on the line VII—VII of Figure 5, showing the machine in various forging positions.

45 In view of the fact that the "Ajax" heading machines are well known in the art and also since the novel features of this invention may be used with other similar machines, the heading machine will not be shown or 50 described in detail.

Referring more particularly to the drawings, the numeral 2 designates the main frame of the machine as a whole, which is provided with suitable guideways for a longitudinally movable cross head 3 and a transversely movable side ram 4. A crank

shaft 5 is journaled in suitable bearings adjacent the rear end of the frame 2 and is connected by gears 6 and 7 with a power shaft 8 journaled in bearings 9 and receiving power through gears 10 and 11 from an electric motor 12.

The crank shaft 5 is connected by a connecting rod 13 with the cross head 3 so as to reciprocate said cross head, and a side arm, designated generally by the numeral 14, is eccentrically mounted on one end of the crank shaft 5 and is connected to the side ram through a knuckle system 14^a so as to reciprocate said ram transversely of the frame 2.

A breast plate 15 is mounted in the forward end of the main frame 2 and is recessed to receive a combined stationary shear and die block 16. The plate 15 and block 16 are provided with a suitable opening 17 through which the bar stock is adapted to be fed by a suitable automatic feed mechanism 18, and the block 16 is further provided at a point to one side of the opening 17 with a die recess 19.

A movable die 20 is mounted in a die holder 21 carried by the cross head 3 and is provided with a die recess 22 adapted to co-operate with the recess 19 in the block 16 to form balls from the stock.

A receiving and holding block 24 is mounted to reciprocate across the breast plate 15, and has its inner end face provided with a semi-circular recess or notch 25. The block 24 is adapted to be moved inward to a point where its inner end face will be in line with the center line of the die recess 19 to receive the pieces of stock from which balls are to be formed and to retain such position until after the stock is engaged by the movable die, and to then be quickly withdrawn out of the path of said die.

The block 24 is adapted to be reciprocated by a rock shaft 26 journaled in bearings 27 on the frame 2 of the machine and having an upwardly extending lever 28 secured to its forward end and pivotally connected to a pin 29 secured in the block 24. A second lever 30 is secured to the opposite end of the shaft 26 and extends upwardly into the path of a cam member 31 carried by the cross head 3. The lever 30 is provided with a roller 32 at its upper end adapted to be engaged by the cam member 31.

A coiled spring 33 is mounted on the shaft 26 under tension and normally tends to rock

the shaft inward to its stock receiving position, where it is held by a stop 34. The cam member 31 is so positioned on the cross head 3 that it will engage the lever 30 after the die 20 has engaged the stock, thus rocking the shaft and positively withdrawing the block 24 from the path of the die.

A movable shear blade 35 is mounted to reciprocate across the breast plate 15 and stationary die and shear block 16. The blade 35 is provided with a semi-circular notch or recess 36 in its inner or shearing end adapted to fit around the stock. The blade 35 is adapted to be moved across the breast plate 15 and engage and cut off the portion of stock projecting through the opening 17 and move said cut piece of stock sidewise across the breast plate and stationary shear and die block and into the notch 25 in the receiving block 24, at which point the stock will be in line with the dies. The shear blade 35 will remain in this position until after the movable die 20 engages the stock, at which time the blade 35 will be quickly withdrawn out of the path of the movable die.

The shear blade 35 is adapted to be moved during its shearing or working stroke by the side ram 4 and to be withdrawn in the reverse direction from the path of the movable die 20 by a rock shaft 38. The shaft 38 is journaled in suitable bearings 39 on the frame 2 of the machine and is provided with an upwardly extending lever 40 on its forward end, which is pivotally connected to a pin 41 secured in the blade 35, and a second lever 42 is secured to the opposite end of the shaft and extends upwardly into the path of a cam member 43 carried by the cross head 3. The lever 42 is provided with a roller 44 at its upper end adapted to ride on the cam member 43.

A coiled spring 45 is mounted on the shaft 38 under tension so as to normally move the blade 35 inward to its stock receiving or shearing position.

The stroke of the side ram 4 is at the same speed in both directions, and, therefore, means must be provided for permitting a quick withdrawal of the shear blade 35 from the path of the movable die. In order to provide a space into which the blade 35 may be moved by the shaft 38 and its actuating cam, a filler block 47 is slidably mounted to be moved between the blade 35 and side ram 4 during the shearing stroke and to be withdrawn just prior to the return movement of the shear blade 35 to provide a space into which said blade may be moved.

The block 47 is mounted on the ram 4 for a sliding movement transversely thereof. The block 47 is adapted to be moved by a lever 48 having one end pivotally connected as at 49 to a pin 50 secured in the block 47 and having its other end secured to a shaft

51 journaled in bearings 52 on the side ram 4. An actuating lever 53 has one end secured to the shaft 51 and its other end is provided with a roller 54 adapted to be engaged by an elongated cam member 55 carried by the cross head 3. The cam member 55 is adapted to operate the lever 53 so as to rock the shaft 51 and withdraw the block 47 from between the side ram 4 and blade 35 and coiled springs 56 and 56' are mounted on the shaft 51 under tension so as to normally rock the shaft 51 in the reverse direction. Therefore, when the shaft is rocked by the cam member 55 to withdraw the block 47, the tension of springs 56 and 56' will be increased, and when the cam member is withdrawn from engagement with the lever 53 the springs 56 and 56' will immediately reversely rock the shaft 51 and return the block 47 to its position between the blade 35 and ram 4.

The die block 16 is provided with a suitable aperture 16' opening into the die recess 19 through which an ejector bar 58 is adapted to reciprocate. The ejector bar 58 is pivotally connected to one end of a rocking beam 59 mounted on a pivot 60 and adapted to be rocked by a reciprocating rod 61 pivoted to the other end of the beam 59. The rod 61 has its forward end pivoted to the beam 59 and its rear end pivoted to the lower end of a rocking beam 62, which is pivotally mounted as at 63 to the frame of the machine and has its upper end provided with a roller 64 adapted to be engaged by a cam 65 on the crank shaft 5.

The movable die 20 is also provided with an aperture 20' opening into its die recess 22, through which an ejector bar 66 is adapted to reciprocate. The aperture 20' is enlarged at its rear end and alines with an aperture in the die holder 21 to form a spring retaining recess 67. The ejector bar has its rear end projected through the recess 67 into a vertically disposed recess 68 in the die holder 21 and is operatively connected intermediate the ends of a vertically disposed operating lever 69, which has its lower end pivotally secured to the die holder 21 and its upper end extended upward into the path of a stationary trip bracket 70.

A coiled spring 71 is mounted around the ejector bar 66 within the recess 67 and is adapted to be tensioned as the bar 66 is moved into the die recess to eject the forged ball, which ejecting movement is caused by the lever 69 engaging against the bracket 70 during the return or backward stroke of the cross head 3, and to, therefore, automatically move the ejector bar out of the die recess 22 when the cross head and die 20 again move in a forward or forging direction.

A stock gage 75, which is part of the standard "Ajax" heading machine is shown

in Figure 6 of the drawings. This gage is mounted on a suitable shaft 76 and operatively connected to the other moving parts of the machine so as to swing into position 5 to gage the stock and then swing back out of the path of the other moving parts of the machine. This gage does not form a part of my invention and since it would only tend to confuse the other features of the machine, it has not been shown in the other figures of the drawings or described in detail. It will, of course, be understood that the machine is clearly operative without the gage shown, and that any other suitable 10 gage may be used if desired.

A complete cycle of operation of the machine will now be described. Assuming that the machine is in operation, a hot round stock bar will be fed by the feeding 20 mechanism 18 through the stock inlet opening 17 until it is stopped by the gage 75. The feeding mechanism will then automatically stop and the gage 75 will swing up out of the stock engaging position. The 25 stock receiving block 24 will be in position to receive the piece of stock to be forged into a ball, and the filler block 47 will be positioned between the shear blade 35 and side ram 4. After the gage 75 is raised 30 out of stock engaging position the side ram 4 will move inward, thus forcing the shear blade 35 against the stock to shear off a piece and carry the sheared piece sidewise into the notch 25 in the stock receiving block 24. The blade 35 and block 24 co-operating to hold the sheared piece of stock in line with the recesses 19 and 22 in the die block 16 and movable die 20, respectively.

The cross head 3 will have started forward during the above operations and will move the die 20 into engagement with the piece of stock held by the block 24 and blade 35. The cam arm 55 carried by the cross 40 head 3 will engage the roller 54 on lever 53 and rock the shaft 51 and lever 48 to positively withdraw the filler block 47 from between the side ram 4 and shear blade 35. Just as the filler block 47 is withdrawn, the cam arms 31 and 43 will engage and operate 45 the levers on rock shafts 26 and 38, respectively, to positively withdraw the stock receiving block 24 and shear blade 35 from the path of the movable die 20 and thus permit the die 20 to force the stock piece into the die block 16 and form a ball. The withdrawal of the filler block 47 gives space into which the shear blade 35 is moved by the cam operated rock shaft 38. As the shafts 26, 38 and 51 are rocked by the cams 31, 43 and 55, respectively, their respective coiled springs 33, 45 and 56, 56' are tensioned so that when the cross head 3 reverses or moves rearwardly and the cams release their respective shafts, such shafts will be automatically rocked in the reverse direction 55

so as to move the stock receiving block 24 into stock receiving position, the blade 35 into position to shear another piece of stock, and the filler block 47 back into position between the ram 4 and blade 35 in readiness 70 to again go through the above cycle of operations.

As the cross head 3 approaches its rear-most position on the return stroke the cam 65 will engage the rocking lever 62 and the lever 69 will engage the trip 70 to operate the ejector rods 58 and 66, respectively, forcing the rods into the die recesses 19 and 22, respectively, to eject the preformed ball if it should stick in either of the dies. 80

While I have shown and described one specific embodiment of my invention, it will be understood that I do not wish to be limited thereto, since various modifications may be made without departing from the 85 scope of my invention as defined in the appended claims.

I claim:

1. A forging machine for forming balls from bars, comprising a main frame, a cross head movable longitudinally of said frame, a side ram movable transversely of said main frame and said cross head, a breast plate mounted adjacent the forward end of said main frame, a stationary die member carried by said breast plate, a second die member carried by said cross head and adapted to co-operate with said first mentioned die member to forge balls from pieces of rod stock, means for feeding stock into said machine in a direction parallel to the longitudinal axis thereof and at a point to the one side of said stationary die, a shear blade mounted to move transversely of said main frame, to shear off measured pieces of stock and move said pieces into line with said dies, said shear blade being moved during its shearing stroke by said side ram, a filler block adapted to be moved into position between said ram and said shear blade prior to said shearing stroke and to remain in such position during said stroke, means for moving said filler block into position between said blade and said ram, a receiving block movable transversely of said frame and adapted to co-operate with said shear blade to position and hold the cut stock in line with said dies until after said stock is engaged by said movable die, means operable by said cross head for positively moving said shear blade and said receiving block out of the path of said movable die, means for positively withdrawing said filler block from its position between said shear blade and said side ram, and means for returning said blade and receiving block to normal position. 110

2. A forging machine for forming balls from bars, comprising a main frame, a

- cross head movable longitudinally of said frame, a side ram movable transversely of said main frame and said cross head, a breast plate mounted adjacent the forward 5 end of said main frame, a stationary die member carried by said breast plate, a second die member carried by said cross head and adapted to co-operate with said first mentioned die member to forge balls from 10 pieces of rod stock, means for feeding stock into said machine in a direction parallel to the longitudinal axis thereof and at a point to the one side of said stationary die, a shear blade mounted to move transversely of said 15 main frame, to shear off measured pieces of stock and move said pieces into line with said dies, said shear blade being moved during its shearing stroke by said side ram, a filler block adapted to be moved into 20 position between said ram and said shear blade prior to said shearing stroke and to remain in such position during said stroke, resilient means for moving said filler block into position between said blade and said ram, a 25 receiving block movable transversely of said frame and adapted to co-operate with said shear blade to position and hold the cut stock in line with said dies until after said stock is engaged by said movable die, means operable by said cross head for positively moving said shear blade and said receiving block 30 out of the path of said movable die, other means operable by said cross head for positively withdrawing said filler block from its 35 position between said shear blade and said side ram, and resilient means for returning said blade and receiving block to normal position.
3. A forging machine for forming balls 40 from bars, comprising a main frame, a cross head movable longitudinally of said frame, a side ram movable transversely of said main frame and said cross head, a breast plate mounted adjacent the forward end 45 of said main frame, a stationary die member carried by said breast plate, a second die member carried by said cross head and adapted to co-operate with said first mentioned die member to forge balls from 50 pieces of rod stock, means for feeding stock into said machine in a direction parallel to the longitudinal axis thereof, and at a point to the one side of said stationary die, a crank shaft journaled in said frame, a connecting rod connecting said crank shaft and said cross head so as to reciprocate said cross head, a shear blade mounted to move 55 transversely of said main frame to shear off measured pieces of stock and move said pieces into line with said dies, said blade being moved during its shearing stroke by said side ram, a receiving block movable transversely of said frame and adapted to co-operate with said shear blade to position and hold the cut stock in line with said dies until after said stock is engaged by said movable die, means operable by said cross head for positively moving said shear blade and said receiving block 60 out of the path of said movable die, resilient means for returning said blade and receiving block to normal position, and means for ejecting the balls from said dies.
5. A forging machine for forming balls 65 from bars, comprising a main frame, a cross head movable longitudinally of said frame, a side ram movable transversely of said main frame and said cross head, a breast plate mounted adjacent the forward end of said main frame, a stationary die member carried by said breast plate, a second die member carried by said cross head and adapted to co-operate with said first mentioned die member to forge balls from pieces 70 of rod stock, means for feeding stock into said machine in a direction parallel to the longitudinal axis thereof, and at a point to the one side of said stationary die, a crank shaft journaled in said frame, a connecting rod connecting said crank shaft and said cross head so as to reciprocate said cross head, a shear blade mounted to move transversely of said main frame to shear off measured pieces of stock and move said 75 dies until after said stock is engaged by said movable die, lever mechanism for positively moving said shear blade and said receiving block out of the path of said movable die, cam members carried by said cross head for operating said lever mechanism, and resilient means for returning said blade and receiving block to normal position.
4. A forging machine for forming balls 80 from bars, comprising a main frame, a cross head movable longitudinally of said frame, a side ram movable transversely of said main frame and said cross head, a breast plate mounted adjacent the forward end of said main frame, a stationary die member carried by said breast plate, a second die member carried by said cross head and adapted to co-operate with said first mentioned die member to forge balls from pieces 85 of rod stock, means for feeding stock into said machine in a direction parallel to the longitudinal axis thereof, and at a point to the one side of said stationary die, a crank shaft journaled in said frame, a connecting rod connecting said crank shaft and said cross head so as to reciprocate said cross head, a shear blade mounted to move transversely of said main frame to shear off measured pieces of stock and move said 90 pieces into line with said dies, said blade being moved during its shearing stroke by said side ram, means operable by said crank shaft for reciprocating said side ram, a receiving block movable transversely of said frame and adapted to co-operate with said shear blade to position and hold the cut stock in line with said dies until after said stock is engaged by said movable die, means operable by said cross head for positively moving said shear blade and said receiving block 95 out of the path of said movable die, resilient means for returning said blade and receiving block to normal position, and means for ejecting the balls from said dies.
5. A forging machine for forming balls 100 from bars, comprising a main frame, a cross head movable longitudinally of said frame, a side ram movable transversely of said main frame and said cross head, a breast plate mounted adjacent the forward end of said main frame, a stationary die member carried by said breast plate, a second die member carried by said cross head and adapted to co-operate with said first mentioned die member to forge balls from pieces 105 of rod stock, means for feeding stock into said machine in a direction parallel to the longitudinal axis thereof, and at a point to the one side of said stationary die, a crank shaft journaled in said frame, a connecting rod connecting said crank shaft and said cross head so as to reciprocate said cross head, a shear blade mounted to move transversely of said main frame to shear off measured pieces of stock and move said 110 pieces into line with said dies, said blade being moved during its shearing stroke by said side ram, a receiving block movable transversely of said frame and adapted to co-operate with said shear blade to position and hold the cut stock in line with said dies until after said stock is engaged by said movable die, means operable by said cross head for positively moving said shear blade and said receiving block 115 out of the path of said movable die, resilient means for returning said blade and receiving block to normal position, and means for ejecting the balls from said dies.
5. A forging machine for forming balls 120 from bars, comprising a main frame, a cross head movable longitudinally of said frame, a side ram movable transversely of said main frame and said cross head, a breast plate mounted adjacent the forward end of said main frame, a stationary die member carried by said breast plate, a second die member carried by said cross head and adapted to co-operate with said first mentioned die member to forge balls from pieces 125 of rod stock, means for feeding stock into said machine in a direction parallel to the longitudinal axis thereof, and at a point to the one side of said stationary die, a crank shaft journaled in said frame, a connecting rod connecting said crank shaft and said cross head so as to reciprocate said cross head, a shear blade mounted to move transversely of said main frame to shear off measured pieces of stock and move said 130 pieces into line with said dies, said blade being moved during its shearing stroke by said side ram, a receiving block movable transversely of said frame and adapted to co-operate with said shear blade to position and hold the cut stock in line with said dies.

pieces into line with said dies, said blade being moved during its shearing stroke by said side ram, a receiving block movable transversely of said frame and adapted to 5 co-operate with said shear blade to position and hold the cut stock in line with said dies until after said stock is engaged by said movable die, means operable by said cross head for positively moving said shear blade 10 and said receiving block out of the path of

said movable die, resilient means for returning said blade and receiving block to normal position, ejector plungers adapted to enter through the rear face of each of said dies, and separate means for automatically operating each of said plungers. 15

In testimony whereof I have hereunto set my hand.

THOMAS A. GORMAN.
